UNITED STATES PATENT OFFICE.

JACK GAUGHAN, OF LONG BEACH, CALIFORNIA.

STOVE.

Application filed August 2, 1922. Serial No. 579,277.

To all whom it may concern:

Be it known that I, JACK GAUGHAN, a citizen of the United States, residing at Long Beach, in the county of Los Angeles and State of California, have invented certain new and useful Improvements in Stoves, of which the following is a specification.

This invention relates to a convertible 10 multiple fuel stove and has for its object the production of a simple and efficient stove which is so constructed as to permit the same to be utilized for the purpose of burning different kinds of fuel, should it become necessary to do so.

Another object of this invention is the production of a simple and efficient stove which is so constructed as to radiate the maximum amount of heat in proportion to 20 the amount of fuel used.

With these and other objects in view this invention consists of certain novel constructions, combinations and arrangements of parts, as will be hereinafter fully described 25 and claimed.

In the drawings:—

Figure 1 is a vertical section through the stove, showing the heating dome arranged thereon,

30 Figure 2 is a section taken on line 2—2 of Figure 1, and

Figure 3 is a section taken on line 3—3 of Figure 1.

By referring to the drawings it will be seen that 1 designates the base of the stove which is supported upon the usual legs or other supports 2. A compartment 3 is formed in the base 1 of the stove, this compartment being formed in any suitable or desired shape or design to accommodate the will of the manufacturer. It is essential, however, that the compartment 3 be of suitable size to permit the insertion of different forms of fuel containers such, for instance, 35 as a grate, an oil burning lamp, an electric grill, or a gas heating burner. It should be understood, however, that it is not desired to limit the present invention to any particular form of heating means, for the present invention is especially designed to accommodate itself to different forms of heating fuel and permit the different forms of heating fuel to be conveniently used without the necessity of re-arranging the design or construction of the stove. For this reason the compartment 3 is made of suit- 40 able size to accommodate the various forms of fuel which may be used.

A suitable integral door 4 is employed, having a suitable window 5 formed therein, and a suitable draft damper 6, of any suitable or desired form, is also formed upon the door. In the illustration shown in Figure 1 a heating gas burner 7 is employed which is fed by means of a feed pipe 8, a suitable valve 9 being carried by the pipe 8 to control the passage of fuel through the pipe 8.

An oval or egg shaped dome constituting 45 an outer casing 10 is supported upon the base 1 and this dome 10 preferably is provided with a narrowed end 11 indicated clearly in Figure 1, the dome being broadened out toward the top thereof to facilitate the radiation of the heat. A deflector wall 12 is interposed between the lower end of the dome or outer casing 10 and the top of the base 1 for the purpose of directing the heat up into the dome, this deflector wall 12 being inclined inwardly toward the top 50 thereof. The outer casing 1 is provided at the upper end thereof with a narrowed discharge flue 13 to permit obnoxious gases, smoke and other gases to pass off from the heating compartment 3. An operating 55 crank shaft 14 is journaled within the discharge spout 13 and this operating crank shaft 14 supports a suspended valve 15. This valve 15 is adapted to normally control the opening and closing of the vent 60 16 which is formed in the upper end of the inner casing or housing 17 illustrated in Figure 1. In use, the valve 15 is opened when the stove is heated and remains open until the fuel is extinguished, when the valve 15 is closed. In this way the air within the casing 17 is hot when the valve is closed and this hot air tends to retain the casing 17 warm a long period of time after 65 the fuel has been extinguished. If the casing were allowed to be open and air allowed to circulate therein, the casing would soon become cooled off. As shown in Figure 1 it will be seen that the inner housing or casing 17 is substantially the same shape as the outer housing or casing 10, the walls of the casing or housing 17 being uniformly spaced from the walls of the outer casing 10. The lower end of the inner casing or housing 17 is supported upon a substantially 70 cone shaped or funnel shaped crown sheet 18 which is adapted to spread the

flame from the burner 7 or the heat from any other substituted heating means, so as to cause the heat to pass up between the walls of the inner heating drum or casing 17 and the outer casing 10. The lower end of the drum or casing 17 is supported and spaced from the outer casing 10 by means of suitable spacing members 19.

From the foregoing description and by 10 carefully considering the drawings it will be seen that the outer casing 10, as well as the inner casing 17, is of a balloon like structure, the inner casing 17 constituting a balloon like drum producing a maximum 15 amount of heat radiating surface.

It should be further understood that a very simple and efficient means has been produced in the nature of a stove for permitting various forms of fuel to be substituted without the necessity of reconstructing the form of the stove. It should be understood, however, that certain detailed changes in the design may be employed in the device without departing from the spirit 25 of the invention so long as these changes fall within the scope of the appended claims.

Having thus fully described my invention what is claimed is:

1. A stove of the class described comprising a base provided with a fuel compartment, an ovoidal outer casing formed upon the base having its upper end terminating in a discharge flue, an ovoidal inner casing substantially spaced within the outer casing and provided with a valve seat in its upper end and a valve adapted to be seated in said valve seat to close said inner casing and retain same air-tight.

2. A stove of the class described comprising a base provided with a fuel compartment, said base being narrowed toward

the top, an ovoidal outer casing formed upon the base having its upper end terminating in a discharge flue, a cone-shaped deflector plate positioned at the entrance of said outer casing, an ovoidal inner casing mounted within the outer casing on the cone-shaped plate and provided with a valve seat in its upper end and a valve adapted to be seated in said valve seat to close said inner casing and retain same air-tight. 45

3. A stove of the class described comprising a base having a comparatively large compartment formed therein to accommodate itself to various forms of fuel, said base being contracted near the top thereof to form an inclined deflector wall, an outer casing of a balloon like structure formed upon said deflector wall, and terminating in a discharge flue at the outer end thereof, an inner casing of a balloon like structure arranged in spaced relation with respect to the outer casing and provided with a detachable substantially funnel-shaped crown sheet at the lower end thereof adapted to fit directly above said inclined deflector wall, for spreading the heat from the base and causing the same to pass up between the inner and outer casings, brackets carried by said outer casing to support said inner casing and to hold said inner casing in spaced relation thereto, said inner casing being provided with a vent opening at the upper end thereof and a valve adapted to close said vent opening and retain the inner casing air-tight. 55

In testimony whereof I affix my signature in presence of two witnesses.

JACK GAUGHAN.
